DESIGN FOR A PACKAGE HANDLE OR SIMILAR ARTICLE

Joseph E. Miano, New York, N. Y.

Application February 22, 1944, Serial No. 112,674

Term of patent 14 years

(Cl. D17—5)

To all whom it may concern:

Be it known that I, Joseph E. Miano, a citizen of the United States, residing at New York city, in the county of Bronx and State of New York, have invented a new, original, and ornamental Design for a Package Handle or Similar Article, of which the following is a specification, reference being had to the accompanying drawing, forming part thereof.

In the drawing
Fig. 1 is a perspective view of a package handle showing my new design;

Fig. 2 is a front elevation, and

Fig. 3 is an end view of same.

I claim:

The ornamental design for a package handle or similar article, substantially as shown.

JOSEPH E. MIANO.
